UNITED STATES PATENT OFFICE.

JOSEPH PRICE, OF STAPLETON, NEW YORK, ASSIGNOR TO THE GRISCOM-RUSSELL COMPANY, OF NEW YORK, N. Y., A CORPORATION OF DELAWARE.

CONDENSER-TYPE HEATER.

Application filed March 13, 1925. Serial No. 15,185.

The present invention relates to a fluid to fluid heat exchanger and has to do particularly with large capacity units wherein the heating medium is steam at relatively low pressure.

In steam utilizing plants it is common to employ the various heat returns from the system, such as exhaust steam from the auxiliary apparatus of the plant, bleeder steam from one or more stages of the main turbines, or the like, to preheat the boiler feed water before it is passed into the boiler. In order that a satisfactory overall efficiency may be obtained, it is advisable to heat the feed water as much as practicable by means of used steam. The modern tendency in central station practice is to effect the transfer of the heat from the used steam to the boiler feed water in heat exchangers where- 10 in the water is passed through the heat trans- 15 ferring tubes and the steam is circulated about in the space surrounding the tubes. Condenser type heaters of this character as used in modern power plants are commonly 20 large units. Furthermore, it is desirable 25 that the heating elements of these units be bodily removable from the shell for pur- 30 poses of inspection, cleaning and repair, and it is this feature which gives rise to consid- 35 erable practical difficulty in providing an apparatus wherein the heating element may be readily removed and reassembled after the device is once installed. The necessity 38 of air baffles in the lower part of the shell is chiefly responsible for such difficulties of manipulation.

It is a principal object of this invention to provide a condenser type heater of this class intended to effect a heat transfer between water and steam. The invention contemplates an effective heat interchange between the two mediums, a complete condensation of the heating steam and provision for the separation of entrained air from the heating medium and its discharge from the apparatus. The tube bundle which constitutes the heating element of the apparatus is a large unit consisting of a sufficient number of tubes to present an ample heat transferring surface to the action of the heating steam. The tubes are supported at their respective ends and are provided intermediate their ends with an additional support. An air baffle is provided for effecting sub-cooling and discharge of the air and insur-

ing complete condensation of the vapors so that no condensable vapors will escape through the air vent. The tubes together with the end supports for the tubes, the intermediate tube support, the air baffle and the other elements necessary to the rigidity and strength of the structure are built as a separate unit which is bodily removable from the apparatus shell.

It is an important feature of this invention that the tube bundle and its associated elements are assembled and secured in place within the apparatus shell as a single unit, and in such fashion as to render removal and reassembly of the unit easy. In the large capacity heat exchangers of the general type referred to herein, I have found that in order to manufacture the apparatus according to commercially practicable methods, provision must be made for variations in the position of the respective elements when assembled in the shell, sagging of the tube bundle, differences arising out of expansion and contraction under influences of temperature change and the like. The invention contemplates connections for assembling and securing in place the heating element of the apparatus which connections are flexible in the sense that they permit a limited amount of variation in the position of the parts and the like and in this way facilitate assembly of the apparatus and afford an apparatus wherein the tube bundle is capable of being removed and replaced with a minimum amount of time and effort.

It is a further object of this invention to provide an air baffle for permitting discharge of uncondensable vapors and at the same time preventing discharge of condensable vapors, which baffle is incorporated as a part 95 of the heating element so that it is removed from the apparatus upon removal of the heating element. The air baffle is built into the heating element in such fashion that it may be withdrawn from the tube bundle 100 after the bundle has been removed from the apparatus without necessity of disassembling any of the tubes or other parts of the heating element.

A preferred embodiment of the invention is illustrated in the accompanying drawings wherein Figure 1 is a longitudinal vertical section taken through an apparatus embodying the invention, Figure 2 is a view illustrating the supporting structure for the

removable element, Figure 3 is a transverse sectional view taken through the apparatus of Figure 1, and Figure 4 is a view illustrating a detail.

- 5 Referring to the drawings, 1 indicates the shell or housing of the heater and 2 indicates the tubes which constitute the heat transferring element of the apparatus. The tubes are supported at one end in a stationary tube sheet 3 and are supported at 10 the other end in a tube sheet 4 which, together with the head or chamber 5, constitutes a longitudinally movable support for the tube ends by reason of which the tubes 15 may expand and contract under the influence of temperature change without injury to the parts of the apparatus. Water is admitted to the apparatus through the inlet opening 6 from whence it enters certain of the tubes 20 2. In the apparatus here shown, provision is made for passing the incoming water along the length of the heat transferring element four times before it is finally discharged through the outlet 7. This multi- 25 pass arrangement is effected by means of the partitions 8 within the head 9 at the initial end of the apparatus and by means of the partition 10 within the head 5 at the other end of the apparatus. The water being 30 heated is thus subjected to the action of the heating steam throughout an extended period of time so that an effective heat transfer is secured. Heating steam is admitted through the inlet 11 into the space surround- 35 ing the heat transferring tubes 2 and the condensate is ultimately discharged through the opening 12 provided for this purpose at the bottom of the shell 1.
- The invention particularly contemplates 40 the provision of a heating element which may readily be removed and restored again to operative position. A supporting member or plate 13 is provided intermediate the ends of the tubes 2. The support 13 is 45 here shown positioned about midway between the ends of the tubes and is attached by suitable connections to the shell 1 of the apparatus. As shown in Figure 3, a plurality of bolts 14 are employed to secure the plate 13 to the shell 1. These bolts engage 50 with lugs 15 welded or otherwise secured to the plate 13. Each of the bolts extends to the exterior of the shell through a hole 16 in the shell which is of a diameter materially 55 larger than the diameter of the bolt. Leakage is prevented by introducing a threaded member or plug 17 into the opening 16, which plug is in turn sealed at its end by means of a threaded cap 18. The head 19 60 of the bolt 14 works against a washer 20 at the outer end of the plug 17 to thereby establish the connection between the supporting plate 13 and the shell 1, and can be turned to space the plate 13 farther away 65 from or closer to the shell at the point of connection. The inside diameter of the threaded plug 17 is considerably greater than the diameter of the bolt 14 so that the bolt may be introduced into connection with the supporting plate 13 throughout a con- 70 siderable variation in position of the plate, circumferentially of the shell. The washer 20 is slotted longitudinally as indicated at 75 21 in Figure 4 to thereby accommodate a limited range of positions of the bolt 14, longitudinally of the shell. Thus the connections between the intermediate support and the shell can be adjusted in all three of the possible planes of motion; that is, radially outwardly or inwardly, closer to, 80 or farther away from, the shell; longitudinally of the shell; and circumferentially of the shell, and thereby permit of limited variations in the final and operating position of the support within the shell. This struc- 85 ture provides a rigid connection between the apparatus shell and the tube supporting plate and at the same time permits the limited variation in position of the supporting plate which has been found necessary in order that hurried and easy but efficient and proper securing in position of the removable unit may be accomplished. 90
- The apparatus is provided with air outlets 22. Cooperating with these outlet members are air baffles 23 constituted preferably of flexible sheet metal and secured in place by suitable brackets or plates 24 which serve to attach the baffle to the respective tube supporting sheets or plates. The air outlet members 22 have a threaded connection 25 with the baffle members 23 so that they may be removed by unscrewing them from their connection with the baffles and withdrawing them to the exterior of the shell. Upon removal of the air outlets 22 and the bolts 14 the air baffles 23 are freed from their connection with the shell 1 and may be removed with the heating element. 100
- The frame or skeleton of the removable element is shown in Figure 2. It comprises the tube sheets 3 and 4 together with the middle tube support 13. Tube supporting members or distance pieces 27 are placed at appropriate intervals around the periphery of the unit and extend between the tube sheet 3 and the intermediate tube support 13. For the purpose of providing free expansion and contraction of the tubes under the influence of temperature change, no such distance pieces are provided between the intermediate tube support 13 and the tube sheet 4 at the other end of the unit. If the heater employs tubes of such length that more than one intermediate support 13 is required, distance pieces 27 will be provided between all of the intermediate tube support plates and between the tube sheet 3 and the intermediate plate 13. No distance pieces would be attached to the tube sheet 110

4, namely that tube sheet which constitutes a part of the floating head of the apparatus. The air baffles 23 constitute a part of the removable unit as shown. This frame structure shown in Figure 2 together with the heat transferring tubes 2, which for the sake of clearness have been omitted in the illustration of the figure, constitute the removable element of the apparatus.

10 The air baffle 23 surrounds in large part certain of the tubes of the heating element indicated generally at 26. The purpose of this arrangement is to insure complete condensation of the vapors in the shell and to thus prevent the escape of the condensable vapors through the air discharge outlets. The heating steam admitted to the apparatus through the inlet opening 11 circulates about within the shell 1 and is thus brought into heat 15 transferring relation with the outer surfaces of the tubes 2. The condensate and the uncondensed portion of the heating fluid pass down toward the bottom of the apparatus whereupon the condensate is discharged 20 through the outlet opening 12 and the gases and remaining uncondensed vapors are drawn up within the air baffle into heat transferring relation with the group of tubes 25 26. By the time that the heating fluid has reached the lower portion of the shell, the vapors are substantially completely condensed, but the group of tubes 26 is so arranged as to insure complete condensation of any part of the vapors which may not 30 have been condensed during the normal passage of the heating medium through the apparatus and to subcool the non-condensable gases so as to reduce the volume of said gases. The uncondensable gases such as air and the 35 like pass out through the discharge opening 22, the outward flow of gases being preferably maintained by means of a suitable air pump or the like.

When the removable unit is withdrawn from the shell the air baffle 23 is readily removable from the tube bundle without necessity of taking out any of the tubes or otherwise disassembling the unit. The baffle is made of flexible sheet metal so that by merely loosening its retaining clamps 24 it may be directly withdrawn from its position in the tube bundle. It will be noted that the various clamps in the present structure for the most part occupy otherwise unused space and do not appreciably restrict the amount of heat transferring surface which may be incorporated into the apparatus.

The present invention provides a condenser type heater in which the entire tube bundle is readily removable from the shell and readily replaceable in the shell, in spite of the fact that this type of heater includes an air baffle near the bottom of the shell extending throughout the length of the tubes.

and in addition includes one or more supports for the tubes intermediate their ends. The present structure permits easy and prompt withdrawal of the large tube bundles employed in this type of heater and insures that they may be removed from and replaced in the apparatus easily and accurately in the shortest possible time. The invention resides largely in the particular structure and arrangement employed in incorporating the air baffle and the intermediate tube support into the apparatus not only without interfering with removal of the tube bundle but positively facilitating the assembling of the tube bundle into position in the shell.

I claim:

1. In a heat exchanger of the class described, a shell, heat transferring tubes within said shell, end supports for said tubes, an additional support for said tubes positioned intermediate said end supports, and detachable connections between two of said respective supports and said shell, the detachable connections of said additional support having freedom of motion in three directions, whereby the heating element may be removed as a unit from the shell.

2. In a heat exchanger of the class described, a shell, heat transferring tubes supported at their respective ends, a support for said tubes intermediate the ends thereof, and connections between said intermediate support and said shell, said connections being capable of being established throughout three planes of adjustment at right angles to each other, thereby permitting a limited variation in the positioning of said support within the shell.

3. In a heat exchanger of the class described, a shell, heat transferring tubes within said shell, means for introducing heating fluid to the space within the shell surrounding said tubes, means for discharging gases from the shell, and a baffle cooperating with said discharge means for insuring complete condensation of the condensable vapors and preventing escape thereof, said baffle constituting a part of the tube bundle and being removable therewith. 105 110 115

4. In a heat exchanger of the class described, a containing shell, a tube bundle constituting the heating element of the apparatus, means for admitting heating steam to the space surrounding the tubes of said bundle, discharge means for passing uncondensable gases out of the apparatus, a baffle cooperating with said discharge means for insuring condensation of condensable vapors and preventing escape thereof, and means for securing said baffle in integral relation with said tube bundle, said baffle being bodily removable from the apparatus with said tube bundle and being independently removable from said tube bundle. 120 125 130

5. In a heat exchanger of the class described, a shell, heat transferring tubes positioned within said shell and supported at their respective ends, a support for engaging said tubes intermediate their ends, and means of attachment between said intermediate support and said shell comprising a loose-fitting connection which permits a limited variation in the positioning of said support in the shell, whereby said attachment is capable of being established throughout three planes of adjustment.
6. In a heat exchanger of the class described, a shell for containing the heat transferring medium, heat transferring tubes within said shell, end supports for said tubes, an additional support for said tubes intermediate the ends thereof, and connections between said intermediate support and said shell, comprising a bolt engaging one of said parts and having a connection with the other part over a limited range of positions, whereby said connections are capable of being established throughout three planes of motion.
7. In a heat exchanger of the class described, a shell for containing the heating medium, heat transferring tubes within said shell, end supports for said tubes, an additional support for said tubes intermediate the ends thereof and connections between said intermediate support and said shell comprising a bolt engaging said support and having a limited range of adjustment with respect to said shell, whereby said connections may be established throughout three planes of motion at right angles to each other and variations in position of said support may be accommodated.
8. In a heat exchanger of the class described, a shell for containing the heating medium, heat transferring tubes within said shell, end supports for said tubes, an additional support for said tubes intermediate the ends thereof, connections between said intermediate support and said shell comprising a bolt engaging said support and extending through a hole in said shell of diameter substantially greater than that of the bolt, means for preventing leakage at said connection and a member for effecting the engagement of said bolt with the shell for any of its positions within said hole.
9. In a heat exchanger of the class described, a containing shell, heat transferring tubes within said shell, a stationary tube sheet supporting said tubes at one end thereof, a longitudinally movable tube sheet supporting said tubes at the other end thereof, whereby expansion and contraction of said tubes under the influence of temperature change is accommodated, an additional support for said tubes intermediate the ends thereof, connections between said intermediate support and said shell for rigidly attaching said support to said shell and permitting a limited variation in the position of said support, and spacing members between said respective tube supports, said tubes and tube supports being removable bodily from said shell.
10. In a heat exchanger of the class described, a containing shell, heat transferring tubes within said shell, a stationary tube sheet supporting said tubes at one end thereof, a longitudinally movable tube sheet supporting said tubes at the other end thereof, whereby expansion and contraction of said tubes under the influence of temperature change is accommodated, an additional support for said tubes intermediate the ends thereof, connections between said intermediate support and said shell for rigidly attaching said support to said shell and permitting a limited variation in the position of said support, spacing members between said respective tube supports, said tubes and tube supports being removable bodily from said shell.
11. In a heat exchanger of the class described, a containing shell, heat transferring tubes within said shell, a stationary tube sheet supporting said tubes at one end thereof, a longitudinally movable tube sheet supporting said tubes at the other end thereof, whereby expansion and contraction of said tubes under the influence of temperature change is accommodated, an additional support for said tubes intermediate the ends thereof, connections between said intermediate support and said shell for rigidly attaching said support to said shell and permitting a limited variation in the position of said support, spacing members between said respective tube supports, said tubes and tube supports being removable bodily from said shell, a baffle incorporated as a part of said removable unit for facilitating discharge of uncondensable gases, detachable outlet means cooperating with said baffle for expelling uncondensable gases from the apparatus and means whereby said baffle may be removed from the tube bundle without disassembling of said bundle.

In testimony whereof I affix my signature.
JOSEPH PRICE.
